3 Claims. (Cl. 340—312)

1

This invention relates to an electrical signalling system. More particularly, it deals with a combined in-and-out register and paging system for persons, such as doctors visiting a hospital or the like, in which the presence of any one of a plurality of such persons in a region or building may be indicated, one at a time, at a remote point or station, and any one or more of said persons may be paged by operating a control at said remote station.

It is an object of this invention to provide a simple, efficient, economic and effective in-and-out registering and paging system for persons within a given region.

Another object of this invention is to provide a combined in-and-out registering and paging system which saves time, space, wiring, materials, large conduits, contractor's installing time.

Another object is to provide such a system in which the registering and paging conditions remain operated until they are positively reset even if the power to the system has been cut-off in the meantime.

Another object is to provide such a combined registering and paging system in which a common selecting circuit is employed for indicating the register conditions and for paging the person so selected.

Another object of this system is to provide a telephone operator in a hospital with information immediately as to whether or not any one of a plurality of doctors is in or out of the hospital, and to place a paging signal for him when he passes the register, either coming-in or going-out, if he is to report for a message which the operator has received for him.

Generally speaking, the system of this invention comprises: (1) an entrance register panel for identification of each person to be registered and paged, which panel contains separate registers for each person with the name, corresponding number, a signal device such as a light, and a switch for that person to operate into its "in" or "out" indicating position according to whether that person is entering or leaving the building; (2) an operator's keyboard at a remote station from said panel to indicate selectively the position of the registering switch for each person on the panel; (3) a power supply and flasher unit for the panel and keyboard signal devices; and (4) the necessary electrical wire connections between the three aforesaid parts of the system.

At the entrance registering panel the register for each person thereon contains besides the person's name, number, manual register switch and

5 light, a bi-stable relay which may be operated by the operator at the keyboard for causing the light to flash or not-flash for paging the person so that said person will know if there is a message for him or not at the office for which he must report. The light at the name may be illuminated when the manual switch is operated into its in-position, and may be flashed by the operation of said relay when a message is awaiting that person.

10 At the keyboard, there are provided a plurality of selecting push button or key switches arranged in digital rows corresponding to the digit of the number of the name of the person to be located or paged, as well as a manual detecting switch to indicate, such as by separate lights, whether that person is "in" or "out"; and further separate manual message and reset switches cooperating with the circuits of the selected connection for said person, for causing that person's signal light on the panel to flash or not-flash, if a message is awaiting him or not, respectively.

15 The panel also comprises selective connection relays for connecting any one of the person registers thereon with the keyboard in response to the operation of a selecting numbered push button in each digital row at the keyboard for setting up the number of that person at the keyboard. Each digital row of selecting numbered push buttons or keys at the keyboard may be interconnected, so that only one key in each row can be operated at one time, and each of the keys may operate a pair of separate electrical switches, for controlling the corresponding proper selecting devices of the entrance register panel.

20 The above mentioned and other features and objects of this invention and the manner of attaining them are given more specific disclosure in the following description of an embodiment of this invention taken in conjunction with the accompanying drawings, wherein:

25 Fig. 1 is a schematic diagrammatic showing of the general parts of the system of this invention, adapted for a panel having three hundred separate registers for names, arranged with fifty registers in each of six vertical columns, and a keyboard arranged with three rows of numbers according to the digits of the decimal system;

30 Fig. 2 is a wiring diagram of the power supply and flasher unit shown in Fig. 1 connectable to Fig. 3;

35 Fig. 3 is a wiring diagram of the operator's keyboard shown in Fig. 1 that is connectable to both Figs. 2 and 4; and

40 Fig. 4 is a wiring diagram of the lower left

corner of the entrance register panel shown in Fig. 1, showing eight separate individual registers and their selecting means and how they are controlled by and connected through the circuit and keyboard of Fig. 3 to the power supply unit of Fig. 2.

I. The installation equipment

Referring first to Fig. 1, an electrical current source, such as the ordinary domestic 110-115 volts A. C., may be introduced into the system via conductors 1 and 2 of a cable 3 to the power supply and flasher unit, part or section 4. From this section 4 an electrical cable 5 made up of a plurality of conductors (herein for A. C.) may be connected to a terminal or junction assembly 6, and another cable 7 of a greater number of conductors (herein for D. C.) may be connected to another terminal or junction assembly 8. From this latter assembly 8 a still greater number of separate conductors in a cable 9 may be connected to a remote station or operator's keyboard 10. Between the junction assemblies 6 and 8 there may be a further cable 11 for the selecting means connections, and then these connections together with the power supply conductors in cable 5 may be connected through a cable 12 from the assembly 6 to an entrance register panel 13. This panel preferably is located at the entrance of the region or building for which the system is constructed, so that the persons whose names appear on it may pass it when entering or leaving the building, to operate their respective in-and-out register switches on the panel. This panel herein is shown to be made up of six columns 14 of fifty registers, each register being provided with a separate two position bi-stable toggle switch 15, for indicating the "in" and "out" condition of the person corresponding with that register. Each register also is provided with a separate signal device, such as an electric light 16, which may be masked to shine through a translucent name and/or number plate 17 for the corresponding person on the panel.

Each person on the panel is thus assigned a number, and since herein there are shown to be three hundred names on the panel, there are correspondingly at the keyboard 10 three digits of numbers and three rows 18, 19 and 20 of numbered keys or push-buttons corresponding to the hundreds, tens and units digits of these numbers, respectively. This keyboard 10 is controlled by an operator at a remote station from the panel 13, such as at the telephone operator's switchboard in the office of the building having this system. Each row of buttons may thus be provided with ten numbers from "0" to "9" for each of the digits of the numbers of the persons and each person is provided with a three digit number, in which the "0" button may be pressed for those persons having numbers which are less than three digits. For example, the number "7" would be set-up on the keyboard as "007" in order to make the complete selecting connection as disclosed later in Fig. 3. Rows 18, 19, 20 of keys or push-buttons are preferably mechanically interconnected so that only one button in each row may be pressed at a time and it will remain pressed until another button in that row is pressed.

Also located on the keyboard 10 are three manual switches which only remain closed as long as they are pressed, pushed or held closed. The first one of these three additional switches is a

detecting switch D or 21, which is pushed after the number of the person desired or to be selected has been set up on the rows of keys 18, 19 and 20. Detecting switch 21 then completes the connection through the selective means to the panel 13 for indicating the condition of the manual switch 15 corresponding to said selected or desired person. Other two manual switches M and R or 22 and 23 are for controlling the paging signal for that selected person. The message switch 22 or M causes the light 16 on the panel for that person to flash when that person's register switch 15 is in its in-position, and the other or reset switch 23 or R is for stopping the paging signal so the light 16 will not flash, such as after the person has reported to receive the message which he was paged to receive. The position of the in-and-out or register switch 15 for any selected person on the panel may be indicated at the keyboard 10 by means of separate "in" and "out" lights 24 and 25, respectively, mounted on the keyboard.

II. The power supply

Referring to Fig. 2, the wiring diagram of the power supply unit or section 4 is shown to produce two types of current for the system: alternating current which is conducted through the system over the heavier lines in Figs. 2, 3 and 4 for supplying the signal current for operating the electric lights in the system; and direct currents which may be of different voltages which are conducted through the lighter lines in Figs. 2, 3 and 4 for operating the selecting means comprising different types of relays.

The alternating current supply for the system introduced through conductors 1 and 2, a main manual double pole switch 35 and fuses 31, is preferably transformed in a transformer 32 to a lower voltage alternating current, such as about 12 volts, so that standard smaller lights may be used in the system to conserve space and power. This lower alternating current is conducted directly to the other sections or parts of the system through conductors 33 and 34 from the two output terminals of the transformer 32.

Connected across these conductors 33 and 34 in the power supply unit 4 is a flasher unit (see the upper left corner of Fig. 2). This flasher unit 50 may comprise a mechanical interrupter driven by a small standard A. C. motor 49, which motor may be connected directly to the 110-115 volts source of conductors 1 and 2 through conductors 41 and 42 and another pair of fuses 43, and may 55 comprise a rotating toothed cam 44 driven by the motor 49, which cooperates with a spring applied cam follower 45 coupled to one of a pair of interrupter contacts 46, which are repeatedly opened and closed at a regular rate to apply 60 intermittent current to one or more (depending upon the load) parallelly connected alternating current relays 47 and 48 between the conductors 33 and 34 in series with interrupter contacts 46. Contacts 51 and 52 of the relays 47 and 48, respectively, are connected in parallel with a 65 flashing current supply conductor 53 which extends from the power supply unit 4 of Fig. 2 directly to the panel circuit of Fig. 4 for producing the flashing signal for the lights 16 on the panel. For the purpose of identification, the interrupted or flashing alternating current conductors are 70 shown in the drawings as being a thin continuous line with heavier dashes thereon.

The other and direct current supply for the system, may be obtained from a full wave recti-

fier bridge circuit 60, the alternating current terminals of which may be connected to the output terminals of another transformer 62. The input terminals of this transformer 62 are herein shown to be connected through the pair of fuses 43 directly to the 110-115 volts alternating current leads 1 and 2 through manual switch 30. This transformer 62 may only reduce the voltage to about 60 volts, or to the maximum voltage to be employed for the different selecting means and relays in the panel circuit of Fig. 4.

The output terminals 63 and 64 of the rectifier 60, herein shown to be positive and negative, respectively, may be connected across a condenser 65 to take out the ripples in the rectified current. Also across the output terminals 63 and 64 and parallel with the condenser 65 may be provided a potentiometer which may be composed of two equal resistors 70 and 71 in series (of say 500 ohms), with separate variable taps 72 and 73 to each, positive in potential with respect to a negative end connection 74 connected to rectifier negative terminal 64, and which taps 72 and 73 supply different voltages for operating special relays in the selective circuit means. Connected to the positive terminal 63 of the rectifier 60, is a variable voltage dropping resistance 75 having a tap 76 as a further source of reduced direct current for other and standard type relays in the selecting circuit on panel 13 to be connected through the keyboard 10. The connections and taps 73, 74 and 76 are connected to conductors of corresponding reference characters, and all extend directly to the circuit of the keyboard 10 shown in Fig. 3. The tap 72 of the lowest voltage, however, has in series with its corresponding conductor 72 a very sensitive low current direct current relay 80, the contacts 81 of which operate to illuminate the signal lights 24 and 25 (Figs. 1, 3) in the keyboard 10, through corresponding conductors 84 and 85 which extend to said lights.

In the power supply unit 4, there may be also provided a separate condenser 90 in series with a variable current limiting resistor 91 connected across conductors 93 and 94 which extend to the current reversing or reset switch R or 23 on the keyboard 10 (see Fig. 3) for causing a reverse polarity direct current surge from the condenser to be passed to a selected one of the relays of the panel circuit to release the flashing signal connection therefor as will be described in more detail later.

III. The selecting and registering circuits

Referring now more specifically to Figs. 3 and 4, there are provided in Fig. 3 three rows 18, 19 and 20, of push-buttons or keys, corresponding to the ten numbers in each of the three digits of the three hundred different registers corresponding to the person to be selected and paged according to the present system and provided for on the panel 13. However, since only three numbers of the hundreds digit need be employed, the push-buttons "3" through "9" in row 18 have not been shown to be connected in the present disclosure, but may be provided on the keyboard 10 for further extension of the system if and when desired.

In the panel, the selecting means comprises relays; one hundreds relay H₀, H₁, and H₂ for each hundreds digit with relay H₀ being the only hundreds digit relay shown in Fig. 4; one tens relay T for each tens digit in each hundred, namely thirty tens relays T⁰⁻⁹, T¹⁻⁹ and T²⁻⁹;

and ten units relays U for each tens digit relay, namely three hundred units relays U⁰⁰₀ through U²⁹₉. Each of the hundreds digit relays H and each of the tens digit relays T are provided with ten separate contacts, see relays H₀, T⁰⁴ and T⁰⁹ shown in Fig. 4; or if more practical, a pair of parallel five contact relays may be provided for each of these ten contact relays. These hundreds and tens relays may be standard relay equipment and may be operated by 48 volts taken between conductors 76 and 74 to the potentiometer 70-71 in the power supply unit 4. On the other hand the units relays U are different and specially polarized or bi-stable relays which remain in the position they are set by opposing currents which energize and deenergize them. Eight of such bi-stable unit relays U⁰⁴₆, U⁰⁴₇, U⁰⁴₈, U⁰⁴₉, U⁰⁹₆, U⁰⁹₇, U⁰⁹₈ and U⁰⁹₉ are shown in Fig. 4 there being one for each register for each person provided for on the entrance panel 13.

Thus, if for example and for explaining the operation of the selecting means, the person or doctor having the number "49" or herein "049" is to be selected, to determine if he is "in" or "out," or if he is to be paged, the operator at the keyboard 10 performs the following selection operations: The number corresponding to this person may be determined from a quick index of the names and corresponding numbers of each person on the panel 13, which index may be provided in a card file or on a sheet next to the operator at the keyboard. Once the number "049" is determined, the operator then presses the push-button "0" in row 18, the push-button "4" in row 19, and the push-button "9" in row 20 on the keyboard 10.

The pressing of the push-button "0" in row 18 energizes the hundreds digit relay H₀ in Fig. 4 through a circuit from positive terminal 63, tap 72 and conductor 76 through contact 99 of push-button "0" in row 18, conductor 100, hundreds relay H₀, conductors 101 and 102 to the common negative conductor 74 (Figs. 3, 2). The pressing of push-button "4" in the tens digit row 19, energizes the tens digit relay T⁰⁴ in Fig. 4 through a circuit from positive terminal 63, tap and conductor 76, push-button "4" in row 19, conductor 104, contact 105 of relay H₀, conductor 106, relay T⁰⁴, conductors 107, 108 and 102 to common negative conductor 74. The pressing of push-button "9" in the units digit row 20, however, does not yet energize the corresponding units relay U⁰⁴₉ in the panel 13, but it does prepare a circuit for its operation when either the message switch 22 or the reset switch 23 on the keyboard 10 is operated.

If it is to be determined whether the person corresponding to number "049" is "in" or "out," that is, if he has operated his resistor switch 15 mounted on the panel 13, then only detecting switch 21 is operated by the operator at the keyboard 10. The pressing now of self-release switch 21 completes a circuit to energize the in-and-out indicating relay 80 (see Fig. 2) through the coil of the units relay U⁰⁴₉ if the person is "out," and not to energize this relay 80 if the person corresponding to number "049" is "in," as well as also completing a circuit to light the corresponding light 24 or 25 on the keyboard 10. The light 24 or 25 only remains lighted as long as the switch 21 is maintained pressed.

If the manual register switch 15 for the person "049" is in its "out" position, that is the position shown in Fig. 4, the operation of the detecting

switch 21 to energize the in-and-out relay 80 is as follows: A low positive potential from tap and conductor 72 of potentiometer resistor 70 is passed through in-and-out indicating relay 80, conductor 110, contact 111 of switch 21, conductor 112, contacts 113 of push-button "9" in row 20, conductor 114 to the panel 13, conductors 115 and 116 to the register corresponding to person "049," contact 117 of switch 15 shunting the 1000 ohm resistance 118, conductor 119, through the 1000 ohm coil of the units digit bi-stable or polarized relay U^{049} without operating its armature 120, conductor 121, contact 122 of tens digit relay T^{049} , conductors 107, 108, 102 and 14 to the negative terminal 14 of the potentiometer 70 and negative terminal 64 of rectifier 60. The energization of relay 80 operates its contacts 81 so that "out" light 24 on the keyboard lights through a circuit from one terminal of the transformer 32, conductor 33, front contact 81, conductor 84, "out" light 24, conductor 130, contact 131 of detecting switch 21, conductor 132, contacts 133 of push-button "0" in row 18, conductor 134, contacts 135 of push-button "4" in row 19, conductor 136, contacts 137 of push-button "9" in row 20, conductors 138 and 34 to the other terminal of the transformer 32.

If the person "049" is "in" or has operated his corresponding register switch 15 ("49") into its in-position, a circuit is completed to illuminate his corresponding register light 16 from one terminal of transformer 32, conductors 33, 143 and 144, back contact of armature 120, contact 145 of switch 15, light 16, and conductors 146, 147 and 34 to the other terminal of the transformer 32. This light 16 indicates to any one passing the entrance panel 13, that the person corresponding to register "049" is "in." In such a case, however, the resistance 118 in the register circuit on the panel is not now shunted by the contact 117 of the manual registering switch 15, and there is not now sufficient current in the above traced circuit for even operating the sensitive relay 80 when the detecting switch 21 is operated, so that the armature of relay 80 does not close its front contact 81 but remains against its back contact as shown in Fig. 2. Now, when this condition exists, that is when the person "049" is "in," the operation of detecting switch 21 illuminates or energizes the "in" light 25 through the following circuit from one terminal of the transformer 32, conductor 33, back contact 81, conductor 85, "in" light 25 on the keyboard 10, conductor 130, contacts 131 of detecting switch 21, conductor 132, contacts 133, conductor 134, contacts 135, conductor 136, contacts 137, and conductors 138 and 34 to the other terminal of the transformer 32.

III. The paging circuit

If the selected person is "in," that is he has operated his corresponding register switch 15 to its in-position, and said person is wanted to report to the operator at the keyboard for a message, the operator then presses the message switch M or 22 on the keyboard 10 which flashes the light 16 corresponding to said person, since his light 16 is already illuminated due to the fact that he is "in." This flashing is caused by the energization of his units digit relay U^{049} by bypassing or shunting out the in-and-out indicating relay 80 from the circuit now containing both the resistance 118 and units digit relay coil U^{049} by operating switch 22 even only instantaneously. The circuit for this energization of the units digit relay U^{049} is as follows: Positive potential

from the tap 73 of the potentiometer 70-71 is passed to the keyboard 10, through conductor 150, front contact 151 of message switch 22, conductor 152, back contact 153 of detecting switch 21, conductor 112, contacts 113 of push-button "9" in row 20, conductors 114, 115 and 116, resistance 118, conductor 119, relay U^{049} , conductor 121, contact 122 of tens digit relay T^{049} , and conductors 107, 108, 102 and 14 to the negative terminal 64 of the rectifier 60. The energization of unit relay U^{049} may move its armature 120 to the other position than that shown in Fig. 4 against the action of a spring 141, and maintain them in said position so that the other switches and selecting push-buttons of the keyboard may be released and reset for other register numbers, detections and operations without thereafter affecting the position of said units digit relay U^{049} . This is also true even if the power supply fails, the setting of the units relays will remain unchanged during the time the power is off and after it is turned on again, and until their position is positively changed by the operation of the release or reset manual switch 23 on the keyboard 10 by the operator.

The flashing of the light 16 on the panel corresponding to the paged person numbered "049," is effected by connecting one terminal of the light 16 to the interrupter current from one terminal of transformer 32, through conductor 33, interrupter contacts 51 and 52, conductors 53, 160 and 161, front contact of armature 120, contacts 145 of manual switch 15, light 16, conductors 146, 147 and 34 to the other terminal of the transformer 32.

The flashing of the light 16 continues until the person "049" operates his register switch 15 to turn off the light 16 entirely, but when switch 15 is turned on again its in-position the light will immediately start to flash again; or until the operator at the keyboard operates the release or reset button 23 to apply an equal and opposite surge of potential to the units digit relay U^{049} from that potential employed in energizing it to move its armature 120 into the position not shown in Fig. 4. If this person "049" had been paged and had answered his paging signal by reporting to the operator, his paging signal may then be cancelled by the operator after setting up his corresponding selecting push-buttons in rows 18, 19 and 20 on the keyboard 10, and then pushing or operating the release or reset switch R or 23 to deenergize his units relay which had previously been energized by the message switch M or 22.

If the person "049" is "out" and is to be paged when he enters the building the message switch M or 22 can be operated to energize his units digit relay U^{049} the same as before, so that when the person "049" does operate his register switch 15 his signal light 16 will immediately start to flash to tell him that a message is awaiting him.

Normally and during the time that the reset switch 23 is not operated, a circuit is maintained from the positive terminal 13 of the potentiometer 70-71, through back contact 170 of reset switch 23, conductor 93, condenser 90, resistance 91, conductor 94, back contact 171 of reset switch 23, conductor 172 to negative conductor and terminal 74 to maintain a charge on the condenser 90, so that conductor 93 is at a positive potential and conductor 94 is at a negative potential.

Now when the reset switch 23 is operated, even

instantaneously, by the operator at the keyboard when the keyboard is set for a selected register to connect with its corresponding units digit relay U, a reversal of the normal direct current for energizing said units digit relay U is applied to it, namely for the units digit relay U⁰⁴, as follows: Positive potential from conductor 93 from one terminal of condenser 90 through front contact 174 of reset switch 23, conductors 172, 102, 108 and 107, contacts 122 of tens digit relay T⁰⁴, conductor 121, units digit relay U⁰⁴, conductor 119, contacts 117 or resistance 118, conductors 116, 115 and 114, contacts 113 of push-button "9" in row 20, conductor 112, contacts 153 of detecting switch 21, conductor 152, contacts 151 of message switch 22, conductor 175, front contact 176 of reset switch 23, conductor 94 and resistance 91, to negative terminal of the condenser 90. The normally maintained charge on the condenser 90 thus is discharged through the units relay U⁰⁴ to deenergize it and cause it to kick its armature 120, aided by the action of spring 141, back into its deenergized position as shown in Fig. 4. This disconnects the flashing current to the light 16 at the panel register and the light then burns continuously until the register switch 15 is moved to its out-position as shown in Fig. 4, if it is not already in said position.

Instead of the spring 141 for making the units digit relays U bi-stable, these relays U may be polarized or have special cores which have the desired degree of residual magnetism. The taps on the variable resistances 70, 71 and 91 may be adjusted according to the sensitivity of the units digit relays and the "in" and "out" indicating relay 80, to effect the above described operations.

Accordingly, the system of this invention enables a person in such an in-and-out registering and paging system to be both registered and paged over the connections and conductors of the selecting circuit for that person's register at a remote station, thereby materially reducing the number of wires and conductors required.

While there is described above the principles of this invention in connection with specific apparatus, it is to be clearly understood that this description is made only by way of example and not as a limitation to the scope of this invention.

What is claimed is:

1. A combined in-and-out register and paging

system, comprising: a register panel having a separate register for each person to be paged, each register comprising a signal light and a circuit including a manually operated switch having in-and-out positions for energizing and de-energizing said light, selective means at said panel for individually selecting one of said registers responsive to a plural digit number transmitted thereto, a keyboard remote from said panel having means thereon for transmitting plural digit numbers one at a time to said selective means for connecting a corresponding one of said registers to said keyboard, an in-and-out indicating means at said keyboard, circuit means including a detecting switch at said keyboard for operating said indicating means corresponding to the position of said manually operated switch of the connected selected register, other circuit means including a paging switch and said selective means connections for causing said signal light to flash when said manual switch is at its in-position, and further circuit means including a releasing switch and said selective means connections to prevent said signal light from flashing when said manual switch is at its in-position.

2. A system according to claim 1 including a direct current source wherein said selective means includes bi-stable relays for each register and means for energizing said relays by passing a direct current from said source through said relays in one direction.

3. A system according to claim 2 wherein said further circuit means includes a condenser for discharging current through said relays in an opposite direction to that employed for energizing said relay to release said relays.
